UNITED STATES PATENT OFFICE.

CHARLES HILAIRE HENRI RODANET, OF VERSAILLES, FRANCE, ASSIGNOR TO SOCIETE ANONYME ETABLISSEMENTS ED. JAEGER, OF LEVALLOIS, FRANCE, A COMPANY OF FRANCE.

ELECTRICAL MEASURING APPARATUS.

Application filed March 17, 1927, Serial No. 176,217, and in France March 19, 1926.

This invention relates to improvements in the construction of electrical measuring apparatus, and more particularly in the construction of ammeters. Important features 5 of the present invention are the special mounting and form of the indicating needle or pointer, and the special devices adopted to ensure a strong precise apparatus, capable of being made by repetition work. In its 10 preferred form the casing of the apparatus comprises interiorly two partitions and a boss diametrically opposed and presenting parallel grooves or gaps in which the extremities of a laminated core, surrounded by a coil 15 connected to the control circuit, engage. The boss is formed with lateral housings for the poles of an annular permanent magnet, also a housing for the members serving as bearings 20 for one of the extremities of the axle of the needle, and also a sector-shaped compartment. The members serving as bearings for the other 25 end of the needle axle are constituted by a plate and a bridge piece secured to the said boss. The sector-shaped compartment receives two blades formed on the lower limb 30 of the needle and set perpendicularly to its plane, which in conjunction with the sector-shaped compartment constitute a damping system for the movable elements.

35 Solid with the axle of the needle is an armature. A feature of the constructional arrangement above described is that the axis or centre of gravity of the needle armature coincides with the point of crossing of the polar axis of the permanent magnet with the vertical axis of the laminated core of the coil, the consequence being that the needle is extremely sensitive.

40 The preferred embodiment of the above features of novelty will now be described more fully with reference to the accompanying drawings in which:—

45 Figures 1 and 2 are respectively a front elevation and a vertical cross section of apparatus in accordance with the present invention.

Figure 3 is a perspective view on a larger scale, partly in section.

50 The cylindrical casing 1 of the apparatus is formed or provided internally in its upper part with two converging partitions 2 and in its lower part with a trapezium-shaped boss 3, the two converging sides of which are situated in the diametric planes containing respectively the two partitions 2. The casing

1 also comprises three internal bosses 4 for receiving the fixing screws 5 of a glass cover frame 6 which serves to close the said casing 1.

The transverse partitions 2 are each provided with a shoulder piece 7 outwardly inclined with respect to the depth of the casing. The trapezium-shaped boss 3 has formed on the shorter of its parallel faces a groove 8 of rectangular section, also outwardly inclined. On the two converging sides of the boss 3 are formed cylindrical housings 9 to receive the ends or poles of an annular permanent polarized magnet 21. The boss 3 is also formed with a truncated conical recess or bore 10 surmounting a sector-shaped compartment 11.

The top and bottom ends of an assembly of sheets 12 of a laminated core are housed respectively in a gap or groove between the free ends of the shoulder pieces 7 of the partitions 2 and in the groove 8 of the boss 3, the bottom end of each sheet being composed of a triangular portion and a horizontal extension or shoe 13. The laminated core is surrounded by a sleeve 14 of insulating material 80 (bakelized cardboard for example). The extremities of the sleeve 14 fit into or against upper and lower insulating washers 15 bearing respectively against the shoulder pieces 7 and the shoes 13 of the sheets 12 of the core. 85

Between the washers 15 an insulating plate 16 is held on the bottom of the casing 1. This plate 16 is fastened in place by means of fixing bolts 17, which pass through the bottom of the casing 1 and serve on the inside of the 90 casing as terminals 18, and on the outside of the casing engage connecting leads 19, permitting the connection of the apparatus with the general circuit which controls it. The terminals 18 receive the ends of an insulated 95 wire 20 which forms the coil around the laminated core.

In the truncated bore 10 located between the poles of the permanent magnet 21 is mounted a movable armature carrying the 100 indicating needle or pointer 24. The armature is composed of juxtaposed sheets 22 integral with the axle 23 of the needle 24, the latter being fixed between the front pair of the sheets 22. The needle 24 is cut from a 105 metal plate and has, on its lower limb two blades 25 which are folded back at right angles to form a kind of U-shaped member. This member oscillates during angular movements of the needle 24, in the sector-shaped 110

compartment 11 formed in the boss 3. This in its entirety forms an air damper.

The axle 23 of the needle 24 is mounted on pivots like those used in clockwork. For this purpose each of its pivot forming extremities passes through the central bore of a mounting member and rests on a jewelled counter-pivot member 27. The rear mounting member or guide 26 and its counter-pivot member 27 are lodged in the truncated bore 10. The other mounting member or guide and its corresponding counter-pivot member are constituted respectively by a plate 28 and a bridge piece 29, which are assembled 15 in juxtaposition on the boss 3.

A sector 30, of transparent material, permitting the adjustment of the damping system of the needle 24 closes the compartment 11.

20 The casing 1 is closed by the dial 31 and is provided with a dial frame 6 with glass face 32, completing the apparatus.

What I claim is:—

1. In an electrical measuring instrument 25 such as an ammeter, involving the presence of a magnet and an indicating needle, the latter having an armature, a casing having an internal boss, said boss being recessed laterally to receive the polar ends of the magnet 30 and said casing being formed adjacent said boss in a bore in which the needle axle and its armature are enclosed.

2. In an electrical measuring instrument 35 such as an ammeter, a casing, a permanent annular magnet therein, a current-carrying coil and laminated core set with their axial plane crossing the polar axis of said magnet, a pivoted indicating needle having its axle coincident with the intersection of the afore- 40 said axial plane and polar axis, an armature solid with said axle, two internal partitions in the casing presenting at their free ends a

gap to house the upper end of the coil surrounded core, and a diametrically opposite internal boss having a groove to house the 45 lower end of the said core.

3. In an electrical measuring instrument such as an ammeter, a casing, a permanent annular magnet therein, a current-carrying coil and laminated core set with their axial 50 plane crossing the polar axis of said magnet, a pivoted indicating needle having its axle coincident with the intersection of the aforesaid axial plane and polar axis, an armature 55 solid with said axle, two internal partitions in the casing presenting at their free ends a gap to house the upper end of the coil surrounded core, and a diametrically opposite internal boss having a groove to house the 60 lower end of the said core, said boss having a bore in which the needle axle and its armature are enclosed.

4. In an electrical measuring instrument such as an ammeter, a casing, a permanent annular magnet therein, a current-carrying coil and laminated core set with their axial 65 plane crossing the polar axis of said magnet, a pivoted indicating needle having its axle coincident with the intersection of the aforesaid axial plane and polar axis, an armature 70 solid with said axle, an extension of the indicating needle beyond its axis of rotation, two internal partitions in the casing presenting at their free ends a gap to house the upper end of the coil surrounded core, a diametrically opposite internal boss having a 75 groove to house the lower end of the said core, and an annular chamber in the shape of a cylindrical sector co-operating with the said extension of the indicating needle to 80 constitute an air damper.

In testimony whereof I have signed my name to this specification.

CHARLES HILAIRE HENRI RODANET.
